UNITED STATES PATENT OFFICE

WARREN S. WATTS, OF LOUISVILLE, KENTUCKY, ASSIGNOR TO ARLETTE, INC., OF LOUISVILLE, KENTUCKY, A CORPORATION OF DELAWARE

HAIR-WAVING SACHET

Application filed April 24, 1929. Serial No. 357,626.

The present invention has to do with a device used for encasing a lock of hair which has been twisted or rolled upon an iron for forming in such lock of hair what is known as a permanent wave, and resides particularly in the structural details of such an encasing device whereby it is adapted to be formed to adapt itself to a series of particular conditions confronting a hair dresser.

The article hereinafter described and illustrated overcomes certain difficulties encountered in connection with devices used for similar purposes, and provides a unique arrangement of parts possessing distinct advantages over earlier forms. Like other forms invented by applicant, it possesses an adaptability for production as an article of manufacture at very low cost. In addition to providing such advantages of manufacture, the article has a very pleasing appearance.

The objects of the invention include, among others, the following:

A wrapper of hair sachet pleasing to the eye, durable in construction, and economical of manufacture, in which the window may be differently disposed at the option of the producer.

A wrapper or sachet simple in structural features and formed of components readily adjusted to dispose the opening in the pad holding section so that it may be a large or small opening as selected.

Improved structural features facilitating superior "curling" action upon the hair brought about by differently disposing the window in the pad holding section.

A unique casing for an absorbent pad which provides means for conveniently adjusting the opening therein both as to size and as to position.

A casing for metallic foil extending behind an absorbent pad and comprising a simplified assembly of parts whereby different sized and positioned openings in association with said pad may be readily obtained.

The objects hereinabove referred to, and such other objects as may hereinafter appear, are obtained by the novel construction, arrangement, and combination of the several

elements forming the article herein described and fully illustrated.

One form only of the invention is illustrated in the accompanying single sheet of drawing hereby made a part of this specification, and in which

Figure 1 is a plan view of a blank used for forming the casing;

Figure 2 is a fragmentary view of the end portions of the blank shown in Figure 1, partially assembled and illustrating the method of forming the pocket therein;

Figure 3 is a plan view of the metallic foil sheet used in association with the casing;

Figure 4 is a plan view of the textile pad which is adapted to be associated with the casing and foil;

Figure 5 is a plan view of an assembled sachet; and

Figure 6 is a transverse section of the complete sachet shown in Figure 5 and is taken on the line 5—5 thereof.

Like reference characters are used to designate similar parts in the drawing and in the description of the invention hereinafter given.

Reference should be had first to Figure 1. In said figure, there is shown a blank which may be parchment or other paper, or of other suitable sheet material selected for the purposes of the invention.

The numeral 10 is used to designate the main body portion of said blank. This particular section of the body is of greater area than any of the remaining sections of the casing blank. Section 10 and the adjacent portion forming the inside of the finished sachet are separated by a fold in the assembled device (represented in Figure 1 by a dotted line 11). Such inside portion is marked 12, and one face of section 10 forms the exposed back portion of such sachet.

Appended to section 10 is an extension 13 which comprises, in the assembled device, one layer or lamination of an envelope or pocket formed in conjunction with the material at the other end of the blank.

Depending from the opposite side of the blank and appended to section 12 and separated therefrom by an incision 14 is such por-

tion of the blank as is employed for forming the front of a pocket to receive a pad, such pocket forming section including a projecting windowed section and a section 15 which is generally rectangular and which forms the back of such pocket. When assembled, these sections are separated by a fold on the dotted line 16.

Intermediate sections 12 and 15 and separated therefrom is the windowed section 17, the opening therein being designated 18. Such window is of any suitable size. It should not be so large that a pad to be inserted into the pocket may accidentally slip therefrom. In practice, the pad may be adhesively secured at its back to the material of the pocket.

At each end of the section 17 and separated therefrom by folds represented by dotted lines 19 and 20, are lateral extensions 21. To form the pocket, designated as a whole 22, the section 12 is folded forwardly on the fold line 11 and over the part identified by the numeral 10, after which the ends 21 are folded upon the lines 19 and 20 to lap over and upon the back of section 13. Ends 21 are adhesively secured to section 13, and then member 15 is folded on line 16 and adhesively applied over ends 21 and the remaining exposed section of member 13.

Thus the pocket 22 is formed, there being an opening 18 in the one layer front 17 of said pocket, and a laminated back comprising sections 13, 21 and 15. The manner of folding the blank shown in Figure 1 whereby to obtain pocket 22 is best illustrated in Figure 2. This assembly is made only with the foil sheet hereinafter described in its proper relation to the casing sections.

Heretofore it has been usual to dispose the window 18 centrally of section 17. For rolls, and other special undertakings and conditions, the window may be differently disposed as is herein shown. The resulting structure places the pad so that one edge is wholly free from covering by envelope material. Such a pocket is said to have an open end. This end may have a wide or narrow or no strip covering whatever, and likewise opening 18 may be so formed in section 17 as to provide a narrow or wide band across the closed end of the pocket. The invention relates particularly to a pocket opening, its proportions, and the relation of the opening bears in position to section 17.

Figure 3 illustrates a sheet of foil material 30 having an extension portion 31, these two sections being integral. For convenience of description, an imaginary divisional line 32, in dots, is shown. The portion 30 corresponds with section 10 of the casing blank and in the assembled article extends approximately to the right-hand edge thereof as shown in Figure 1, but does not extend quite to the left-hand edge thereof.

Normally the foil reaches to approximately one half inch from the left-hand edge of said section 10. It is not desirable to have metal or metallic foil come into direct contact with the human scalp, hence there is a small amount of clearance at the left-hand end of section 10 and over which the foil sheet does not extend.

The foil which is employed may be plain foil or it may be a backed foil. When backed foil is used, it may have a paper backing. Preferably a backing is employed, for this diminishes the amount of metal required because thinner metal may be used and it reduces the danger of damage to the foil sheet without disturbing the other characteristics which make foil desirable for use in hair sachets.

In assembling the device, the foil extension 31 is inserted into pocket 22. Usually the section 31 is adapted to completely fill the pocket 22 whether the opening 18 is large or small and irrespective of its position upon section 17. When a backed foil is used the metal surface is uppermost.

When there is a backing upon the foil, such backing will come directly in contact with the inner face of portion 10 of the casing, and the backing on section 31 of the foil will come into contact with the inner face of portion 13 of the pocket. When so inserted and disposed, the casing is assembled as previously directed.

Reference will now be had to Figure 4. This shows a pad of absorbent material upon which a solution used for softening and/or curling the hair is disposed. Such solution may be of any of the usual ingredients now employed or any which may be discovered in the future. The pad generally comprises a highly absorbent material like felt enclosed within a harder material like that employed for bandages or surgical gauze. While the core or interior portion of the pad is generally a section of soft felt, any other absorbent material may be employed without departing from the spirit of the invention.

The entire pad is designated 40, and it is adapted to be inserted into and is inserted into pocket 22 in assembling the complete device, the back of the pad 40 resting upon the front surface of the section 32 of the foil sheet. The front portion of such pad 40 is exposed through the window 18, so much of the surface of pad 40 being exposed as is determined by the maker of the sachet. In the present form one edge of the pad is exposed, and most of the outer surface of said pad is in front of the said window 18 so that liquid therein may readily come into contact with the curled hair.

For holding the pad 40 within the pocket in envelope 22 and for holding the foil extension 31 also therein, a stitching 41, shown in Figure 5, is employed. There may be slits

or openings in the face of section 17 to provide for releasing moisture or liquid which might otherwise accumulate in the corners of the envelope 22, such openings being designated by the ordinal 23.

- 5 Preliminary to use, the pad 40 may be charged in any of the conventional manners. It may be dipped into a solution which is to be used thereon, or such solution may be made 10 to impregnate the pad by the use of a pipette, a measuring device, or any other selected instrumentality whereby such solution is transferred from a container to the pad 40. As it is now recognized that a definite quantity of 15 a solution of any fixed characteristic should be employed for each curl, it is quite usual to pour a measured quantity of the selected solution upon a pad 40.

In the finished sachet, when in flat form, 20 there is exposed a section of foil 30 several inches in breadth and approximately one inch in length and having the casing at the back side only thereof. This right-hand end of the sachet, Figure 5, is twisted or crimped 25 about or beyond said rod, there being sufficient body in the sheet of foil to insure that such sachet, when so crimped, will permanently be held about the lock of curled hair until the proper time for its removal after the 30 heat of the hair curling machine has been applied thereto.

The sachet, after the pad 40 therein has been moistened, is wrapped about a lock of hair which is twisted upon a suitable curling 35 rod or iron. That part of the sachet comprising two thicknesses of paper without an intermediate foil section is disposed adjacent to the scalp. The pad portion 40, of course, is the first portion to be wrapped about the 40 hair. When the entire sachet is wrapped around the curled lock of hair upon the curling rod or iron about which the hair is twisted, the hair and iron are covered.

Such a sachet as is here illustrated provides 45 an impervious section through which the moisture from the pad 40, even when converted into steam, cannot readily escape to the outside atmosphere. It thus insures the full benefit of the moisture contained in the pad 50 for steaming and curling the hair and the whole effect of the chemical ingredients employed thereon for the treatment of softening of the hair.

As presented, the device comprises three 55 sections, each adapted to be produced separately in a machine, there being a relatively simple assembly therebetween. The position of opening 18 in section 17 does not affect such assembly or the characteristics of any part of the device. One fastening number is all that 60 is required to maintain the three parts in their assembled relation, thus, the cost of production and of assembly is very low.

I claim:

- 65 1. A blank for forming a sachet for hair

waving and comprising a body section having an extension providing at one side thereof an open edged pocket to receive an absorbent pad, the material of said pocket being adapted to marginally cover three sides of a 70 pad inserted thereinto.

2. A blank for forming a sachet for hair waving and comprising a body of material adapted to be folded to provide a casing for a sheet adapted to be inserted therein, there 75 being extensions adapted to project from said body to provide an open edged pocket at one side to receive an absorbent pad, the material of said pocket depending over three sides of a pad therein to retain such pad therein.

3. A blank for forming a sachet for hair waving and comprising sheet material adapted to be folded upon itself to provide a casing, each section of said material having an extension, one of said extensions having a 80 window therein and being adapted with the other extension to form a pocket to receive an absorbent pad, there being an open side in said pocket to expose an edge of said pad.

4. A blank for forming a sachet for hair waving and comprising a blank adapted to be folded upon itself to provide a casing for an inserted sheet, said blank having at each 85 end an extension cooperating with the extension upon the other end to form a pocket 90 open at one edge and with pad retaining sections of material at the other edges of the opening.

5. A sachet for hair waving comprising a sheet of material cut and folded to form a body section having an extension at one side providing a four edged pocket to receive an absorbent pad and in which the material of said pocket at three edges thereof depends over a pad therein.

6. A sachet for hair waving comprising a sheet of material adapted to be folded to provide a flat casing, said sheet having extensions projecting therefrom to form a pocket, and said extensions being secured one to the other to surround an absorbent pad on three edges and leaving a section of one edge thereof exposed.

7. A sachet for hair waving comprising a pocket for an absorbent pad and having portions extending over several edges of such pad and leaving an opening to expose the remaining edge of said pad.
